HEAT-TREATMENT APPARATUS

John A. Redmond, Baltimore, Md., assignor to
 Westinghouse Electric Corporation, East Pittsburgh, Pa., a corporation of Pennsylvania

Application August 12, 1950, Serial No. 179,077

2 Claims. (Cl. 219—47)

1

This invention relates to multiple frequency heat-treatment systems, and in particular to the arrangement of heating units therein.

The apparatus of the prior art, of which I am aware, has the limitation that it is necessary to heat-treat at one time gears having one size only. For a manufacturer of automotive equipment who utilizes a mass-production conveyor system and requires for it several sizes of gears, it is necessary to stock-pile heat-treated gears of one size while gears of another size are being heat-treated. The only way to provide heat-treated gears at the necessary relatively continuous rate with the heat-treatment apparatus of the prior art is to heat-treat gears of each desired size in greater quantities than the production assembly line would require during the periods necessary to individually heat-treat gears of all other required sizes.

According to teaching of other prior art with which I am familiar, the necessary continuous flow of heat-treated gears in all required sizes can be maintained by providing an individual heat-treating apparatus for each such desired gear size. For example, if an automobile manufacturer requires five different sized gears in an automobile transmission, he could set up a separate heat-treatment apparatus for each of the five gear sizes, and feed the output from each heat-treatment apparatus directly to the automotive transmission assembly line.

Both expedients, while useful for many purposes, sometimes involve excessive cost in installation, maintenance and operation.

It is, accordingly, an object of this invention to provide heat-treatment apparatus which will not require the stock piling of heat-treated gears of one size, while said apparatus is heat-treating another sized gear.

Another object of my invention is to provide a single heat-treatment apparatus wherein metallic objects, such as gears, having different physical dimensions can be readily heat-treated.

A further object of my invention is to provide apparatus having a plurality of heating units for the high frequency heat-treatment of metallic objects, which can be supplied power from a single high-frequency source without requiring cumbersome and expensive high-frequency switches.

Still another object is to provide apparatus which will heat-treat gears of various dimensions from a single high-frequency power supply without high-frequency switching.

A still further object is to provide a heat-treatment system wherein different sized gears may be

2

heat-treated at a substantially continuous rate, or as may be required in normal mass-production automotive assembly lines.

An ancillary object of the invention is to minimize the loading effect of an empty induction heating unit in the high-frequency arrangement thereof.

A further ancillary object is to make the impedances of the empty high-frequency inductor coils relatively high as compared to the impedance of the inductor coil in which a metallic gear is being heat-treated.

In accordance with this invention, a first plurality of induction heating coils are provided for the low frequency preheating of metallic gears. A second plurality of induction heating coils, corresponding in number to said low frequency induction heating coils, is supplied with high-frequency current and provided to harden said metallic gears. The high-frequency coils are connected in parallel, and all are supplied power from a common high-frequency source. For each sized gear to be heat-treated, a low-frequency heating coil and a corresponding high-frequency heating coil is provided. The low-frequency heating coils can be supplied from suitable separate power sources, or they can be supplied from respective individual secondary windings fed from a common primary winding. A given metallic gear is first preheated by the low frequency energy until it reaches a desired temperature and metallic condition. Then said gear is transferred to the corresponding high-frequency heating coil where a high-frequency current is applied to heat said

gear to the desired temperature for proper hardness. In general, the necessary low frequency treatment requires an appreciably longer period of time than the high frequency treatment. The gear can then be removed from the high-frequency coil, and given the necessary quench treatment.

At any given instance of time, it is better if only one of the high-frequency induction heating coils has a gear in it undergoing heat-treatment. The remaining parallel-connected high-frequency induction coils are empty, and as such present a relatively high impedance to the parallel-connected circuit. Therefore, the power drain by the empty high-frequency coils is relatively negligible. Some of the high-frequency induction coils may have different dimensions for the heat-treatment of respectively different sized gears. To minimize the power drain of the remaining empty high-frequency induction coils, a powdered iron core may be positioned within said empty coils.

This decreases the loading or the power drain of the empty coils in such a manner that more of the available power can be utilized by the loaded coil.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawing, in which:

The figure shows a multiple frequency heat-treatment system in which the high-frequency induction coils are connected in parallel to a single source of high-frequency energy.

In the figure is shown a multiple frequency heat-treatment apparatus in which a plurality of high-frequency induction coils 10, 12, 14 and 16 are parallel connected to a single source transmission line 18 of suitable high-frequency power. All of said high-frequency inductor coils 10, 12, 14 and 16 may be adapted for the treatment of the same sized gear, or each of them may be designed to treat a different sized gear. The choice of inductor coil size is determined primarily by the relative requirements for the different sized gears to be heat-treated. A plurality of low-frequency induction heat coils 20, 22, 24 and 26 is shown. The latter coils 20, 22, 24 and 26 are positioned adjacent the corresponding high-frequency coils 10, 12, 14 and 16, respectively, so a given gear can be first preheated by a low-frequency coil and moved into the corresponding high-frequency coil for hardening treatment. Each of said low-frequency coils 20, 22, 24 and 26 can be supplied power from respective individual power supplies, or they can be supplied energy from a single low-frequency power source through a transformer 36 having one primary winding 33 and a secondary winding 28, 30, 32 and 34 for each of said low-frequency coils. Positioned to be inserted into one of the high-frequency induction coils 15 there is shown a metallic gear 40 positioned for heat-treatment. Near each of the other high-frequency induction coils 10, 12 and 14 there is shown a powdered iron core 42, 44 and 46, respectively. In the practice of my invention, a metallic gear is generally heat-treated in only one of the high-frequency induction coils at a given time, unless there is sufficient power available to handle more than one loaded coil.

The heat-treatment apparatus shown in the figure operates to apply a multiple frequency heat-treatment to metallic objects, such as gears. Any of the high-frequency induction coils and its corresponding low-frequency induction coil can be designed to heat-treat a different sized gear than the other induction coils. For example, if the apparatus includes four high-frequency induction coils and four corresponding low-frequency induction coils as shown in the figure, metallic gears of four different sizes can be heat-treated by a proper choice of coil dimensions. The smallest gear can be heat-treated in the first pair of heat-treatment coils, for example, coils 10 and 20. The next larger gear in the second pair of heat-treated coils 12 and 22, the third larger gear in the next pair of heat-treatment coils 14 and 24, and the largest gear in the last pair of heat-treatment coils 16 and 26.

The heat-treatment operation at each of said pairs of heat-treatment coils is, in general, the

same. Therefore, the operation of only one pair of coils 16 and 26 will be described in detail.

A gear 40 to be heat-treated is first positioned within the low-frequency induction coil 26. A lift assembly 48 is shown by block diagram, and may be designed and operated as customary within the present skill of the art. Low-frequency power is applied, and said gear 40 is pre-heated for a predetermined period of time, depending upon the material of which the gear is composed and the required preheating temperature for the desired treatment. After the pre-heating treatment is completed, the gear 40 is transferred to the corresponding high-frequency induction coil 16 where it is given a hardening treatment by the application of high-frequency energy for a predetermined period of time. The time duration of the hardening treatment similarly depends upon several factors such as the hardness desired, the depth of penetration of the hardness, and the pitch and width of the gear.

In our practical operation, only one of the high-frequency induction coils 10, 12, 14 or 16 is generally heat-treating a gear at any given time. This allows the available power to be supplied from a smaller power source, than if it were not at this one stage of heat-treatment. The empty parallel connected high frequency coils are no problem as they present relatively high impedance to the whole circuit. The loading effect of the remaining empty high-frequency induction coils, which results in a decrease of power available at the one stage that is heat-treating a gear, can be reduced however by inserting a suitable powdered iron core 42, 44 or 46 within each of the empty coils 10, 12 or 14. The impedance of the coil having a gear in it is much lower than the impedance of any empty coil, but the powdered iron core in each empty coil further increases its relative impedance to correspondingly decrease the loading effect thereof.

Although I have shown and described certain specific embodiments of my invention, I am fully aware that many modifications thereof are possible. My invention, therefore, is not to be restricted except insofar as necessitated by the prior art and by the spirit of the appended claims.

I claim as my invention:

1. In apparatus for the heat treatment of irregular metallic objects, the combination of a first plurality of induction heating units connected in parallel and connected to a suitable source of high-frequency current, a second plurality of induction heating units corresponding in number and respective dimensions to said first plurality of induction heating units, each of the second plurality of induction heating units being connected to a source of low-frequency current, and a plurality of core members corresponding in number to all but one of said first plurality of induction heating units and positioned respectively to occupy the latter units other than said one during a heat-treatment time interval when the latter induction heating units other than said one do not contain metallic objects undergoing heat treatment.

2. In apparatus for the heat treatment of irregular metallic objects, the combination of a first plurality of induction heating units connected in parallel and being connected to a suitable source of high-frequency current, a second plurality of induction heating units corresponding in number and respective dimensions to said

first plurality of induction heating units, each of the second plurality of heating units being connected to a source of low-frequency current, said first and second plurality of heating units respectively having different dimensions for the heat treatment of different-sized metallic gears, and a plurality of powdered iron core members corresponding in number to all but one of said first plurality of heating units and positioned respectively to occupy the latter heating units other than said one during a heat treatment time interval when the latter heating units other than said one do not contain metallic objects undergoing heat treatment.

JOHN A. REDMOND.
